UNITED STATES PATENT OFFICE

153,195

DESIGN FOR AN ICE CREAM DIPPER

William C. Willoughby, Tacoma, Wash.

Application June 17, 1946, Serial No. 130,804

Term of patent 3½ years

(Cl. D44—29)

To all whom it may concern:

Be it known that I, William C. Willoughby, a citizen of the United States, residing at Tacoma, in the county of Pierce and State of Washington, have invented a new, original, and ornamental Design for an Ice Cream Dipper, of which the following is a specification, reference being had to the accompanying drawing, forming a part thereof.

The characteristic feature of my design resides in the bowl portion of the ice cream dipper.

Figure 1 is a side elevation of an ice cream dipper, showing my new design.

Figure 2 is a side elevational view of the other side of the article.

Figure 3 is a top plan view.

Figure 4 is an end elevation as seen from the bowl end.

I claim:

The ornamental design for an ice cream dipper, as shown and described.

WILLIAM C. WILLOUGHBY.
